Primary Examiner — Brett Miller(74) *Attorney, Agent, or Firm* — Cramer Patent & Design, PLLC; Aaron R. Cramer(57) **CLAIM**

The ornamental design for a food cutter, as shown and described.

DESCRIPTION

FIG. 1 is a perspective top front right view of a food cutter, showing my new design;

FIG. 2 is a first side elevation view thereof;

FIG. 3 is a second side elevation view thereof, taken at a ninety degree (90°) from said first side;

FIG. 4 is a top plan view thereof; and,

FIG. 5 is a bottom plan view thereof.

1 Claim, 5 Drawing Sheets(56)
